EXPANSIBLE LINK CHAIN FOR A WRIST WATCH BRACELET OR THE LIKE

William C. Boots, Rumford, R. I., assignor to
Foster Metal Products Incorporated, Attleboro,
Mass., a corporation of Massachusetts

Application January 24, 1952, Serial No. 18,208

Term of patent 14 years

(Cl. D45—4)

To all whom it may concern:

Be it known that I, William C. Boots, a citizen
of the United States, residing at Rumford, in
the county of Providence and State of Rhode
Island, have invented a new, original, and ornamental
Design for an Expansible Link Chain for
a Wrist Watch Bracelet or the like, of which the
following is a specification, reference being had
to the accompanying drawing, forming a part
thereof, in which:

Fig. 1 is a fragmentary plan view of an expans-
ible link chain for a wrist watch bracelet or the
like showing my new design,

Fig. 2 is a similar view illustrating the chain
in an expanded position, the conventional bottom
links being visible between the expanded top
links, and

Fig. 3 is a side elevational view of the chain.

I claim:

The ornamental design for an expansible link
chain for a wrist watch bracelet or the like,
substantially as shown and described.

WILLIAM C. BOOTS.
